BENCH GRINDER

Harper Landell, Fort Washington, and Charles J. Davis,
Philadelphia, Pa., assignors to The Black & Decker
Manufacturing Company, Towson, Md., a corporation
of Maryland

Filed Oct. 20, 1965, Ser. No. 87,727

Term of patent 14 years

(Cl. D37—1)

FIG. 1

FIG. 2

FIG. 3

FIG. 5

FIG. 6

FIGURE 1 is a perspective view of the bench grinder;
 FIGURE 2 is a front elevation;
 FIGURE 3 is a rear elevation;
 FIGURE 4 is a top plan view;
 FIGURE 5 is a bottom plan view;
 FIGURE 6 is an end elevation; and
 FIGURE 7 is a fragmentary section, taken along the lines 7-7 of FIGURE 6.

The dominant features of my design reside in the portions shown in full lines.

We claim:

The ornamental design for a bench grinder, as shown and described.
